UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR A LANTERN.

Application filed October 15, 1925. Serial No. 15,139. Term of patent 14 years.

To all whom it may concern:

Be it known that I, JOSEPH W. GOSLING, a citizen of the United States, residing at Schenectady, in the county of Schenectady, State of New York, have invented a new, original, and ornamental Design for a Lantern, of which the following is a specification, reference being had to the accompanying drawing, forming a part thereof.

The drawing is a front elevation of the ornamental lantern of my invention.

I claim:

The ornamental design for a lantern as shown.

In witness whereof, I have hereunto set my hand this 14th day of October, 1925.

JOSEPH W. GOSLING.
